[57] ABSTRACT

A control system for use with emergency devices utilizes an alarm installation having a plurality of transmitters and a single common receiver. Each transmitter is provided with a "memory" contact which remains closed after the transmitter has generated an alarm signal. An oscillating control voltage is fed from the receiver through the contact to actuate an emergency device at any time after the alarm signal. The memory contact is reset by sending from the receiver a reset pulse voltage having an "on" period longer than that of the control voltage.

FIG. 2

CONTROL SYSTEM FOR AN ALARM INSTALLATION HAVING A REMOTE TRANSMITTER WITH A REMOTELY CONTROLLED EMERGENCY DEVICE

BACKGROUND OF THE INVENTION

This invention relates to a control system which utilizes an alarm installation for signal transmission. Typical fire alarm systems employ a plurality of transmitters stationed at different points in a building, for example, and a single common receiver at another location. Each transmitter is connected by wire to the receiver and sends an alarm signal when it has detected an abnormal environmental state such as smoke or extreme heat. The receiver sounds an alarm upon receipt of the alarm signal. Alarm installations of this type, in general, are used exclusively for generating an alarm and are rarely used for any other purpose. More sophisticated fire alarm systems will be needed in the future to cope with the increasing size and complexity of modern buildings. Besides alarms, large buildings should be provided with emergency fire control and safety devices such as guide lamps, emergency exit lamps, fire shutters, smoke shutters, and smoke exhaust fans as well as fire extinguishers. If the existing fire alarm installation could be partly utilized to control these emergency devices, automatically controlled operation of the system could be achieved at relatively low cost.

Emergency equipment is usually designed to be activated at the first sign of fire. However, such equipment should not always be actuated immediately when a fire breaks out. For example, a fire shutter should not be closed with a person trapped in a room, and smoke exhaust fans need not always be started even though a room has been evacuated. These emergency devices should not be linked directly to fire detectors but should be actuated selectively upon proper judgement of the situation at a central receiving station.

An indicator lamp is sometimes installed at the transmitter site to provide a convenient means for identifying the transmitter which has generated the alarm signal as well as for operational tests. The usefulness of the lamp may be enhanced if it is lighted only when it is really required or is cyclically flickered in order to be more conspicuous to the human eye. In conventional alarm systems, however, the lamp is turned on continuously when the transmitter is actuated.

SUMMARY OF THE INVENTION

The principal object of the present invention is to provide a control system which utilizes a fire alarm installation through which various equipment associated with the transmitter can be operated at any time from the site of the central receiver. Another object of the invention is to provide a control system which utilizes a fire alarm installation to operate various equipment associated with the transmitter at any given time by feeding a control or reset voltage from the receiver site.

A control system which utilizes an alarm installation according to the invention is provided with a "memory" contact which is adapted to be closed in response to the operation of a transmitter. The contact remains closed until a reset voltage is received. By supplying a control voltage from the receiver to the controlled de-

vice via the memory contact, the device can be actuated whenever required.

The control system according to the present invention can accomplish the reset operation by employing a reset voltage which is of the same polarity as that of the control voltage but has a longer "on" period than that of the control voltage.

BRIEF DESCRIPTION OF THE DRAWINGS

FIG. 1 is a schematic circuit diagram illustrating an example of a control system of the present invention.

FIG. 2 is a schematic circuit diagram illustrating an example of a controlled device.

DESCRIPTION OF THE PREFERRED EMBODIMENT

Referring now to FIG. 1, a receiver 10 comprises a power supply 2, an alarm relay 4, an oscillator 6, a transistor switching circuit 12 responsive to the oscillator 6, and a relay 8 controlled by the circuit 12. One end of the power supply 2 is connected to a terminal t_1 of the receiver through a stationary contact 8b and a moving contact 8c of the relay 8, and the other end thereof is connected to a terminal t_2 of the receiver through a reset key K2 and the alarm relay 4. The contacts 8b and 8c are normally closed. The relay 8 also has a stationary contact 8a which is connected to the other end of the power supply 2 through a resistor R1. A control switch K1 operates the oscillator 6 which may be a multivibrator or other conventional type of oscillator. When the control switch K1 is closed, the oscillator 6 is energized by the power supply 2 and generates a rectangular pulse voltage consisting of an on period and an "off" period. The generated voltage of rectangular wave shape is produced at output terminals t_5 and t_6 of the oscillator 6. The switching circuit 12 includes transistors Tr₁ and Tr₂. The collector of the transistor Tr₁ is connected to the emitter of the transistor Tr₂ through a register R₄, and the emitter of the transistor Tr₂ is connected to the terminal t_7 which is connected to one end of the power supply 2. The terminal t_6 is connected to the other end of the power supply 2 through a resistor R₆. The base of the transistor Tr₁ is connected to the output terminal t_5 of the oscillator 6 and also is connected to a capacitor C₁ through a resistor R₂ and a diode D₁. The junction of the capacitor C₁ and diode D₁ is connected to one end of the power supply 2 through a reset key K₃, and the other end of the capacitor C₁ is connected to the other end of the power supply 2. The base of the transistor Tr₂ is connected to the collector of the transistor Tr₁ through a resistor R₅, and the collector of the transistor Tr₂ is connected to the other end of the power supply 2 through the coil 8d of the relay 8.

A pair of external lead wires l_1 and l_2 are connected to terminals t_1 and t_2 of the receiver, and the lead wires l_1 and l_2 run a transmitter 20 representative of a plurality of similar transmitters installed in monitored areas.

The transmitter 20 has a diode bridge 22, a controlled device 24, an operation memory contact 26a and a reset circuit 40 therefor, a thyristor switching element SCR₁, and a sensing element or detector 32. The input terminals of the diode bridge 22 are connected to the lead wires l_1 and l_2 through the transmitter terminals t_3 and t_4 , and the output terminals of the diode

bridge 22 are connected to bus wire lines l_3 and l_4 in the transmitter 20. Due to the function of the diode bridge 22, the polarity of the voltage which appears at the bus wires l_3 and l_4 is constant irrespective of connection polarities of the lead wires l_1 and l_2 to the transmitter 20, thereby preventing erroneous operation of the transmitter 20. As shown in FIG. 2, the controlled device 24, in this example, is a relay which has a contact 24a adapted to control an emergency device 30 which may be a guide lamp, a fire shutter, a smoke exhaust fan, or other device. Alternatively, an indicator lamp to indicate the operation of the transmitter 20 may be used instead of a relay for use in the controlled device 24.

The operation memory contact 26a is preferably a contact of a latching relay 26 which has a set coil R_p and a reset coil R_s . Turning to the set circuit, the set coil R_p is connected between the bus wires l_3 and l_4 in series with a diode D_3 , a capacitor C_4 and a resistor R_{10} . A resistor R_9 is connected in parallel with the set coil R_p and the diode D_3 . In the reset circuit 40, the reset coil R_s is connected between the bus wires l_3 and l_4 in series with the memory contact 26a, a diode D_2 and a thyristor SCR_2 . A capacitor C_3 is connected in parallel to the thyristor SCR_2 and the reset coil R_s . The trigger electrode of the thyristor SCR_2 is connected to the bus wire l_4 through a resistor R_8 and also is connected to a triggering capacitor C_2 through a zener diode Z_D . The capacitor C_2 is connected to the bus wire l_3 through the parallel circuit consisting of a resistor R_7 and a diode D_5 and through the memory contact 26a.

A sensing element 32 is used to provide an output signal in response to change in the environmental condition. A conventional type of sensor may be used for the sensing element 32. One end of the thyristor SCR_1 is connected to the bus wire l_3 , and the other end of the thyristor SCR_1 is connected to the bus wire l_4 through a capacitor C_5 . The capacitor C_5 is connected to the resistor R_{10} through a diode D_4 .

Under the normal monitored environmental condition, the power supply 2 of the receiver 10 supplies power through the lead wires l_1 and l_2 to the bus wires l_3 and l_4 . When fire breaks out, the sensing element 32 produces an output signal with which the thyristor SCR_1 is triggered and driven into the on state. The capacitor C_5 , which is connected in series with the thyristor SCR_1 , normally is discharged through the resistor R_{10} . When the output signal is applied from the sensing element 32, the lead wires l_1 and l_2 are short-circuited with the thyristor SCR_1 and the capacitor C_5 and, consequently, the alarm relay 4 in the receiver 10 is energized to generate an alarm signal and to close its self-holding contact 4a. In the transmitter, the capacitor C_4 is normally charged by the bus wires l_3 and l_4 through resistors R_9 and R_{10} . When an output signal is applied from the sensing element 32 and the thyristor SCR_1 is driven into the on state, the charge of the capacitor C_4 is discharged through the circuit consisting of the diode D_3 , the set coil R_p , the thyristor SCR_1 and the diode D_4 , thereby energizing the set coil R_p of the latching relay. Consequently, the contact 26a is closed and the controlled device 24 alone is connected to the bus wires l_3 and l_4 . However, because the self-holding contact 4a of the alarm relay 4 is closed, the lead wires l_1 and l_2 are short-circuited and provide no voltage and, therefore, the controlled device 24 is not energized.

For the controlled device 24 in this example, a relay coil of the slow releasing type is employed. For actuating the controlled device 24, the control switch K_1 of the receiver 10 is closed. When the switch K_1 is closed, the oscillator 6 generates a pulse signal whose on period is shorter than its off period. This pulse signal is applied to the transistor Tr_1 from the terminal t_5 . As the pulse signal is applied, the transistor Tr_1 energizes the relay 8 intermittently via the transistor Tr_2 , thereby switching its movable contact 8c between its stationary contacts 8a and 8b repeatedly. When the contact 8c is thrown into contact with the contact 8a, a negative voltage is supplied to the lead wire l_1 and a positive voltage is applied to the lead wire l_2 energizing the controlled device 24 at the transmitter site. The contact 24a (FIG. 2) is closed thereby starting the actuating motor, for example, of the emergency device 30. Since a slow releasing relay is used for the controlled device 24 which is intermittently energized, its contact 24a is prevented from synchronous on-off operation. However, if an indicator lamp is used in place of the controlled device 24, the lamp is on-off controlled with the control voltage to indicate the operating state.

When the voltage is intermittently applied to the lead wires l_1 and l_2 , the bus wires l_3 and l_4 are not short-circuited by the thyristor SCR_1 even if it is turned on by the output of the sensing element 32. This is because the capacitor C_5 has already been charged or is instantaneously charged when the voltage is applied. The capacitor C_2 of the reset circuit 40 is energized when the voltage is intermittently fed to the lead wires l_1 and l_2 . However, the terminal voltage of the capacitor C_2 does not rise to a sufficiently high level to break down the zener diode Z_D , because the charge of the capacitor C_2 is discharged through the diode D_5 and the controlled device 24 during the off period of the pulse voltage.

The memory contact 26a can be reset by momentarily closing the reset key K_3 of the receiver 10. When the reset key K_3 is closed the capacitor C_1 is charged with the voltage of the power supply 2. The charge of the capacitor C_1 is discharged through the circuit consisting of the diode D_1 , the resistor R_2 , the base and emitter of the transistor Tr_1 , plus the resistors R_3 and R_6 . During the period for which the discharge current flows, the relay 8 is kept energized and its moving contact 8c is kept in contact with its stationary contact 8a for a longer period of time, thereby providing a pulse current of a wider pulse width or on period to the transmitter 20. The capacitor C_2 of the transmitter 20 is charged for a longer period of time and the terminal voltage of the capacitor 20 ultimately reaches a level sufficiently high to drive the zener diode Z_D into the reverse conducting state. As the zener diode Z_D becomes conductive, the thyristor SCR_2 is triggered into the conducting state and consequently the reset coil R_s is energized. As a result, the memory contact 26a is reset or opened and the controlled device 24 is de-energized or turned off.

As described above, this invention provides means to selectively control emergency devices which are related to alarm-generating sensors, simply by adding to an already-installed fire alarm installation, the oscillator circuit 6, the controlled device 24, the memory contact 26a, and the reset circuits 28 and 40 for use with the memory contact 26a. It is possible to automatically start the emergency device by driving the control switch K_1 with the alarm relay 4, if desired. Simulta-

neous resetting of the alarm relay 4 and the controlled device 24 can be achieved by breaking the reset key K₂ (FIG. 1). Since the contact 26a "memorizes" that the sensing element 32 has generated an alarm, the memory contact 26a is not reset even when the lead wires l₁ and l₂ are de-energized and, therefore, the controlled device can be immediately operated when the control pulse is supplied.

Thus, the circuit described above can be easily adapted to perform different operations, for example: selective remote activation and deactivation of emergency equipment; automatic activation and selective remote deactivation of equipment; and automatic or selective remote activation and deactivation of a flickering indicator light or other signal means at the transmitter site. This versatility allows a variety of uses of the same alarm system. The system is shown in connection with fire detection apparatus only for illustration, and is similarly applicable where conditions other than fire, such as nuclear radiation, are being monitored at a central station with one or more detection sites.

The present invention is not limited to the above illustrated example but can be embodied in various ways within the scope and spirit of the appended claims.

We claim:

1. A control system for an alarm installation equipped with a receiver adapted to be connected to a power supply and having alarm relay means, and a remote transmitter connected through lead wires to said receiver, said transmitter having a sensing element for detecting an abnormal condition and a switching element to actuate said alarm relay means in said receiver by connecting said lead wires, wherein the improvement comprises: said receiver including a self-holding alarm relay contact responsive to actuation of said alarm relay means to connect said lead wires and means for selectively introducing a control voltage and a different reset voltage into said lead wires, and said transmitter including a controlled device and a memory switch serially connected between said lead wires, a latching relay responsive to detection by said sensing element for closing said memory switch to connect said controlled device between said lead wires to receive said control voltage when introduced, said latching relay holding said memory switch closed until said reset voltage is introduced by said receiver, said control voltage operating said controlled device without opening said memory switch.

2. The control system of claim 1, further comprising an indicator lamp which serves as said controlled device.

3. The control system of claim 1, further comprising a slow releasing relay having a contact to control an emergency device which serves as said controlled device.

4. A control system utilizing an alarm installation, comprising a receiver adapted to be connected to a power supply and having alarm relay means; a sensing element located remotely from said receiver for detecting an abnormal condition; two lead wires connecting said sensing element to said receiver; and a transmitter which has a thyristor responsive to said sensing element to connect said lead wires to drive said alarm relay means; said receiver having a self-holding alarm relay contact responsive to said alarm relay means for de-energizing said lead wires and said receiver having means to introduce into said lead wires a pulse control

voltage consisting of alternately repeated on and off periods and also to introduce a reset voltage, the on period of which is longer than that of said pulse control voltage, said transmitter having a capacitor which is connected in series with said thyristor to cut off said thyristor after being charged, a discharge resistor which is connected in parallel with said capacitor, a slow-releasing relay which controls an emergency device, and a memory contact which closes when said thyristor is driven into the conductive state by said sensing element for connecting said slow releasing relay to said lead wires until said reset voltage is applied.

5. The control system of claim 4, wherein said transmitter has a latching relay with a setting coil, a resetting coil and a contact serving as said memory contact, said set coil closing said memory contact when said set coil is energized by the discharge current of said capacitor when said lead wires are connected by said thyristor, another thyristor interconnecting said memory contact and said resetting coil with said lead wires, said resetting coil being energized to open said memory contact when said other thyristor is driven into the on state, and a trigger capacitor for driving said other thyristor above a predetermined level by said reset voltage.

25 6. The control system of claim 4, wherein said means of introducing said pulsed control voltage and said reset voltage includes a control relay with a coil and a relay contact for cutting out a certain section of said lead wires and connecting the power supply to the cut-out section, an oscillator for supplying control voltage to said control relay coil, a control switch for operating said oscillator, a reset capacitor for supplying reset voltage to said control relay coil, and reset switch means for charging said reset capacitor.

30 7. A control system for selectively energizing a controlled device through an alarm installation, comprising a receiver having alarm relay means, a remote transmitter having a detector for producing an alarm signal indicative of an abnormal condition and switch means responsive to said alarm signal, an electrical circuit between said transmitter and receiver interconnecting said alarm relay means and said switch means, said switch means closing said circuit in response to said alarm signal to energize said alarm relay means, said transmitter having a memory switch for interconnecting the controlled device to said circuit in response to said alarm signal, said receiver having means responsive to said alarm signal for de-energizing said circuit without deactivating said alarm relay means to prevent said alarm signal from directly activating said controlled device, and said receiver having means for selectively energizing and de-energizing said controlled device via said circuit and said memory switch.

55 8. The system of claim 7, wherein said means for energizing and de-energizing said controlled device produces in said circuit a first pulse voltage having a regular on period to activate said controlled device.

60 9. The system of claim 8, further comprising slow release relay means for interconnecting said memory switch means and the controlled device such that the controlled device is continuously activated by said first pulse voltage.

65 10. The system of claim 8, wherein said energizing and de-energizing means produces in said circuit a second pulse voltage having an on period longer than that of said first pulse voltage, said receiver having means nonresponsive to said first pulse voltage for reopening

said memory switch in response to said second pulse voltage to turn off the controlled device.

11. A control system for an alarm installation, comprising a receiver with a self-holding alarm relay, a remote transmitter with a controlled device and means for generating an alarm signal, electrical lead wires interconnecting said receiver and transmitter, said transmitter having means responsive to said alarm signal for operatively connecting said lead wires to activate said alarm relay in said receiver, said transmitter having latching relay switch means responsive to said alarm signal for simultaneously connecting said controlled device in circuit with said lead wires, said latching relay switch means being resettable to disconnect said controlled device in response to a reset voltage pulse of predetermined minimum duration, means in said receiver responsive to said alarm relay for simultaneously

de-energizing said lead wires, said receiver having means for generating said reset voltage pulse, and said receiver having means for introducing on said lead wires an intermittent regularly repeating pulsed control voltage having an on period less than said predetermined minimum duration for said reset voltage pulse to operate said controlled device on command.

12. The control system of claim 11, wherein said controlled device includes a slow-releasing relay connected in circuit with said lead wires by said latching relay switch means and an emergency device operatively connected to said slow-releasing relay such that said pulsed control voltage is of sufficiently short period to keep said emergency device continuously energized via said slow-releasing relay without resetting said latching relay switch means.
